UNITED STATES PATENT OFFICE.

DAVID W. BLACK, OF BUTLER, PENNSYLVANIA.

ROPE-SOCKET.

SPECIFICATION forming part of Letters Patent No. 499,955, dated June 20, 1893.

Application filed January 23, 1893. Serial No. 459,437. (No model.)

To all whom it may concern:

Be it known that I, DAVID W. BLACK, of Butler, in the county of Butler and State of Pennsylvania, have invented a new and useful Improvement in Rope-Sockets, of which the following is a full, clear, and exact description, reference being had to the accompanying drawings, forming part of this specification, in which—

10 Figure 1 is a longitudinal sectional view of my improved rope socket; and Figs. 2 and 3 are detached views of parts of the same.

15 The object of my invention is to provide an improved rope socket for use as a deep-well tool, and to avoid the disadvantages incident to former rope sockets which have been difficult to apply and often impossible to free from the rope when it is desired to remove them.

20 To this end my invention consists in a rope socket having wedge slips adapted to engage with the ropes, means by which the slips are forced positively against the rope so as to hold the same, and means by which the slips may be withdrawn when it is desired to detach the socket from the rope.

25 In the drawings, 2 represents one of the tubular parts of the socket, having at its lower end the usual threaded portion adapted to be engaged with other tools in the well, and having at its upper portion a male thread and a projecting end constituting the follower 3. On the outer circumference of this end is an annular collar 4. In the lower end of the part 5 of the socket is a recess 6, having a female thread and an inclined seat 7, in which recess the wedge slips 8 are seated, the inclined ends of the slips fitting in the inclined seat. These slips are of segmental conical form and may be of any suitable number, 30 preferably three. On their inner sides they

are preferably serrated so that they may hold the rope securely, and their upper ends are conically tapered so as fit in the tapered seat 7. Near the bottom of these slips are the grooves 9, adapted to engage with the collar 4. 45

The operation is as follows:—The rope 10 is passed through the tubular opening in the part 5 of the socket, into the opening in the part 2, the slips 8 are placed around the collar 4 on the follower 3 and around the rope, 50 and are then inserted in the recess 6, and the two parts 5 and 2 are united by screwing them together, the follower 3 carrying the slips 8 against the seat 7, which forces the slips against the rope so as to hold the same. When 55 it is desired to detach the socket from the rope, the part 2 is unscrewed from the part 5, and as the slips 8 are connected with the follower 3, they may be withdrawn from the recess 6 by sliding the part 5 up on the rope, and 60 being so withdrawn detach themselves from the rope freeing the same.

The advantages of my invention will be apparent to those skilled in the art. The rope socket is simple in construction and is readily applied and removed from the rope. 65

I claim—

A rope socket having a tool connection, an opening for the rope, segmental wedge-slips having an interior groove, a follower having 70 a collar adapted to engage with the groove, and a tapered seat formed in the body of the socket; substantially as described.

In testimony whereof I have hereunto set my hand.

DAVID W. BLACK.
